A new *Petunia* plant particularly distinguished by smaller flower size with a dark violet flower color; medium vigor; and semi-trailing plant habit, is disclosed.

1 Drawing Sheet

1

Genus and species: *Petunia hybrida*.

Varietal denomination: 'KLEPH23557'.

BACKGROUND OF THE NEW PLANT

The present invention comprises a new and distinct variety of *Petunia*, botanically known as *Petunia hybrida* and hereinafter referred to by the variety name 'KLEPH23557'. 'KLEPH23557' is a selection from a controlled cross between the proprietary female *Petunia* line 'PH-2016-2378' (unpatented) and the commercial male *Petunia* line Potunia® 'Cobalt Blue 2016' (patent status unknown).

In July of 2017, the proprietary female *Petunia* line 'PH-2016-2378' and the male *Petunia* line Potunia® 'Cobalt Blue 2016' were cross pollinated in Latina, Italy and seeds were obtained. The seeds were sown and plants were grown for evaluation. A plant line was selected in April 2018 in Latina, Italy and named 'KLEPH23557'. In May 2018, 'KLEPH23557' was first vegetatively propagated by terminal tip cuttings and tissue culture in Latina, Italy. 'KLEPH23557' was found to reproduce true to type in successive generations of asexual propagation via tissue culture and terminal tip cuttings.

SUMMARY

The following are the most outstanding and distinguishing characteristics of this new variety when grown under normal horticultural practices in Latina, Italy.

1. Small flowers with a dark violet flower color;
2. Medium vigor; and
3. Semi-trailing plant habit.

DESCRIPTION OF THE PHOTOGRAPH

This new *Petunia* plant is illustrated by the accompanying photograph, which shows a close-up of the flower of the plant. The plant is about twelve-week-old grown in Stutt-

2

gart, Germany in May 2022. The colors shown are as true as can be reasonably obtained by conventional photographic procedures.

5 DESCRIPTION OF THE NEW VARIETY

The following detailed descriptions set forth the distinctive characteristics of 'KLEPH23557'. The data which 10 define these characteristics were collected from asexual 15 reproductions carried out in Latina, Italy. Data was collected on sixteen-week-old plants grown indoors in Latina, Italy 20 under greenhouse conditions in April 2024. Color references 25 are to The R.H.S. Colour Chart of The Royal Horticultural 30 Society of London (R.H.S.), 5th edition (2007).
